UNITED STATES PATENT OFFICE.

CHARLES F. GRAY, OF SIERRA MADRE, CALIFORNIA, ASSIGNOR TO THE SINGER MANUFACTURING COMPANY, A CORPORATION OF NEW JERSEY.

SEWING-MACHINE.

1,235,793.

Specification of Letters Patent.

Patented Aug. 7, 1917.

Application filed August 25, 1915. Serial No. 47,238.

To all whom it may concern:

Be it known that I, CHARLES F. GRAY, a citizen of the United States, residing at Sierra Madre, in the county of Los Angeles and State of California, have invented certain new and useful Improvements in Sewing-Machines, of which the following is a specification, reference being had therein to the accompanying drawings.

10 This invention, while adapted to loop-takers of different kinds, relates especially to the class of loop-takers performing a plurality of excursions from loop-taking position for each reciprocation of the needles 15 with which they coöperate in the production of stitches; and it has for its object the prevention of the repeated entrance of the same needle-thread loop by the loop-taker beak.

In sewing machines employing plural-rotation loop-takers, it has been the practice to employ a vibratory take-up lever actuated by a crank and link mechanism in order to permit of the high speeds at present demanded, and this has involved the premature commencement of the take-up action and the consequent handling of an excessive amount of needle-thread by the take-up in order to insure the drawing up of the thread-loop discharged by the loop-taker 30 sufficiently early to escape reseizure by the loop-taker beak in its idle excursion.

Another source of difficulty in this class of machines is the sluggish action of the thread-controller or check-spring between the tension device and the needle occasioned by improper adjustment in relation to the size and character of the thread. This is liable to prevent the proper control of the thread-loop shed from the looper-beak in its 40 loop-casting excursion whereby it is caused to be entered by the beak in its succeeding idle excursion.

According to the present improvement, the needle-thread loop shed from the loop-taker beak, and particularly the live or active limb thereof (or that leading through the needle to the take-up), is mechanically controlled by means beneath the work-support and independently of the loop-taker, 50 so as to insure the maintenance of the needle-thread loop out of the range of movement of the loop-taker beak in its idle excursion.

The present improvement is preferably embodied in a loop-taker of the rotary hook

type such as that embodied in the sewing machine represented in my Patent No. 1,115,663, of November 3, 1914, or in my pending application Serial No. 817,737, filed February 10, 1914, the loop-taker being fixed upon a substantially vertical shaft slightly inclined to the path of reciprocation of the coöperating needle upon an axis embraced by a plane transverse to the direction of feed. The loop-taker is preferably formed with a cup-shaped body having a "long beak" with its point at the upper or outer end thereof and provided with a wide annular groove or race-way in the opposite walls of which are journaled the parallel annular supporting ribs or tongues upon the periphery of the thread-case thus sustained by the loop-taker, the said ribs being interrupted upon one side to produce in them respectively thread-catching and thread-detaining shoulders, the one engaging the dead limb of the needle-thread loop or that attached to the material, in the initial portion of the loop-casting operation, while the other prevents the premature release of the loop after the casting operation to prevent entanglement.

The thread-case is preferably provided with a forked lateral lug loosely embracing a holding lug depending from the throat-plate for restraining it against rotation with the loop-taker. The hub or boss of the hook which is secured upon the hook-shaft has preferably formed thereon an actuating eccentric with which is operatively connected a vibratory opener-lever mounted upon a fixed fulcrum and formed with a shoulder adapted to engage the forked thread-case lug to open a passage between the same and the holding lug for release of the needle-thread loop passing through the same to the needle-hole of the throat-plate. The operative portion of this vibratory lever is disposed adjacent the needle-path and intermediate the upper or outer edge of the loop-taker and the throat-plate, and is provided in its lower side with an undercut recess or cavity through which the lower thread normally leads from the thread-case to the needle-hole in the throat-plate. The formation of this recess affords at the end thereof toward which the loop-taker beak moves in its loop-seizing action a lower thread pull-off shoulder and an adjacent spur or finger for shielding the point of the loop-taker beak, an oppositely extending spur or finger

being produced at the other end of the recess serving as a support for the needle-thread loop in and subsequently to the loop-casting operation.

5 As the loop-taker beak reaches loop-shedding position, the opener-lever advances into engagement with the thread-case lug, its pull-off shoulder engaging and drawing off a supply of lower thread for the succeeding stitch in its retiring movement during the final or stitch-setting action of the take-up. The needle-thread loop in the casting operation having been drawn into the recess of the vibratory opener-lever, 10 from the time the thread-loop is shed from the loop-taker beak to the time of its complete release the live limb of the loop rests upon the supporting finger of said lever so as to be forcibly retained out of the path of 15 circular movement of the point of the beak, the point of the beak passing beneath the shielding spur or finger of the opener-lever just as the loop is finally released from confinement between the thread-case detaining 20 shoulder and the heel of the loop-taker for the final stage of the take-up action.

It will thus be seen that the loop-supporting finger is the feature of primary importance of the present improvement in that 30 it holds the thread-loop out of the range of movement of the point of the loop-taker beak, but that this element is materially assisted in the control of the needle-thread loop by the shielding finger which covers 35 the point of the loop-taker beak just as the loop is finally released for the stitch-setting action. It is preferable, although not essential, to form the shielding and supporting fingers upon the opener-lever provided with 40 the pull-off shoulder, in order that these several elements may be confined in a single member in the interest of simplicity and compactness.

45 In the accompanying drawings, only so much of the sewing machine is represented as is directly related to the present improvement, the other parts of the machine being preferably constructed as shown in my said Patent No. 1,115,663. Figure 1 is an elevation representing the needle, loop-taker and take-up with the thread-controlling means beneath the throat-plate in the initial portion of the loop-casting operation, and Fig. 50 2 a plan of such of the same parts as lie beneath the throat-plate in the same positions. Figs. 3 and 4 are similar views with the several parts in the positions which they occupy as the needle-thread loop is about to be shed from the loop-taker beak. Figs. 55 5 and 6 are similar views representing the parts in the positions occupied at the instant of final release of the needle-thread loop preparatory to the stitch-setting action. Fig. 7 is a perspective view of the opener-lever actuating means, Figs. 8 and 9 are

perspective views, taken respectively from the top and bottom, of the arm of the opener-lever containing the loop-controlling elements. Fig. 10 is a perspective view of the loop-taker and Fig. 11 is a perspective view of the bobbin-case.

70 As represented in the drawings, the machine is constructed with a rotary upper or main-shaft 1 with which is connected by means of a well known form of double crank-and-pitman connection the lower shaft 2 rotating in unison therewith. The main-shaft carries the usual crank-arm 3 provided with the lateral stud 4 embraced by the apertured upper end of the pitman 5 75 similarly connected at its opposite end with the stud 6 upon the collar 7 fixed to the reciprocating needle-bar 8 carrying the eye-pointed needle 9.

80 As disclosed more fully in the United States patent to Dial & Dimond No. 695,915, of March 25, 1902, the link 5 has adjacent the crank-pin 4 a laterally offset portion 10 upon which is fulcrumed the bearing sleeve 11. Slidably fitted within 85 the bearing sleeve is the arm 12 of the angular take-up lever mounted upon the fixed fulcrum-stud 13 and provided with the curved operative arm 14 having at its outer end the thread-aperture 15.

90 The needle reciprocates through the usual aperture in the throat-plate 16 which is provided with the depending thread-case holding lug 17. Journaled within suitable bushings in the spaced bearing bosses 18 of a bracket 19 disposed below the throat-plate 100 is the substantially vertical hook-shaft 20 having fixed thereon intermediate said bearing bosses the spiral gear 21 meshing with a similar gear 22 of twice its diameter secured upon the lower shaft 2 which thus 105 imparts to the hook-shaft two rotations for each rotation of the main-shaft 1.

95 Fixed upon and rotating with the upper end of the hook-shaft is the depending hub 110 23 of the cup-shaped body 24 of the hook. The hook is formed with a comparatively long beak 25 having its point slightly below the extreme upper edge of the hook-body 115 which is formed at the opposite or heel portion with divergently extending fingers 26 and 27 forming between them a fork 28 spaced inwardly from and embracing the beak 25. Nearly opposite the throat 29 of the beak the upper portion of the hook-body 120 is cut out transversely to form a thread-drawing shoulder 30.

125 The hook-body is provided with the usual axial thread-cavity in which is formed an annular groove or channel 31 whose opposite side walls constitute the bearing portions of a raceway to which are fitted the corresponding walls of two annular ribs or tongues 32 formed upon and constituting the supporting means for the thread-case 130

33, as shown more fully in my Patent No. 1,008,532, of November 14, 1911. The thread-case is formed at one side of its upper edge with a lateral flange 34 containing the thread-groove 35 through which the lower thread is led to the work from a bobbin 36 within the thread-case. The delivery end of the flange forms one member of a forked lateral lug 37 affording a recess 38 loosely embracing the holding lug 17 depending from the throat-plate.

The center of the cylindrical hub 23 is offset from the axis of rotation of the hook and constitutes an actuating eccentric which 15 is embraced by a strap 39 at one end of a short link 40 whose apertured opposite end embraces a stud 41 upon one arm 42 of a rock-lever whose hub 43 is fulcrumed upon the stud 44 sustained by the bracket 19, and 20 whose oppositely and upwardly extending angular arm 45 has upon its upper extremity a countersunk seat 46. Within the seat 46 is secured by means of the screw 47 the shank portion of an arm 48 whose contracted outer end is bent around the top of the loop-taker so as to move upon the fulcrum-stud 44 in a path substantially tangential to the path of movement of the point of the loop-taker beak at loop-seizing 25 position, or the position in which it enters the thread-loop presented by the needle. The reduced outer portion of the arm 48, which constitutes a part of the vibratory lever 42 43 45, slightly overhangs the conical upper portion of the hook and the circular path of movement of the point of the beak, and therefore lies between the same and the bottom of the throat-plate.

The outer portion of the arm 48 is 43 formed in its under side with an elongated undercut recess or cavity 49 thus producing oppositely extending fingers 50 and 51 with a lower thread pull-off shoulder 52 at the base of the finger 50, an abrupt contact shoulder 53 being provided laterally of the base of the finger 51 for engagement with the side of the thread-case lug 37 opposite the flange 34, as represented in Fig. 4.

As will be later more fully described, the 50 finger 50, the top of which lies intermediate the plane of movement of the point of the loop-taker beak and the throat-plate, constitutes a loop-support upon which a limb of the thread-loop is placed by the loop-taker in the initial stage of its loop-shedding action, where it remains until released from the loop-taker at which instant the point of the beak is covered by the flattened shield-finger 51.

60 In the operation of the machine, the needle descends, and as it begins to rise for presentation of a loop of its thread a , the point of the beak 25 enters the thread-loop and in the initial distention thereof draws the live limb a' within the cavity 49 and

over the supporting finger 51, the lower thread b at this time extending from the thread-case through the cavity 49 and above the finger 51 to the needle aperture of the throat-plate, as represented in Figs. 1 and 2. 70

As the hook continues its initial excursion from loop-seizing position, the thread-loop, the dead limb a'' of which remains engaged by the detaining shoulder 32' of the thread-case, is cast about the latter to 75 the loop-shedding position represented in Figs. 3 and 4, wherein both limbs of the needle-thread loop and the lower thread extend through the cavity 49 to the needle-hole. 80

In the continued movement of the hook, the thread-loop is drawn off the point of the beak and along the guard-finger 26 and into the fork 28, being thereafter drawn upwardly upon the discharge finger 27 from 85 which it is released as such finger passes over the detaining shoulder 32'' of the upper bobbin-case rib 32. Just prior to the instant of release of the loop, the point of the beak has passed beneath the shield-finger 51 which is thereby prevented from catching the loop in its second or idle excursion from loop-seizing position and thereby breaking the thread. As represented in Figs. 5 and 6, the needle-thread 90 loop, just prior to its point of release from the loop-taker leads to the needle-hole over the loop-supporting finger 50, so that in the critical stage of movement of the beak its escape from reseizure of the loop is insured. 100

The action of the take-up and of the thread-drawing shoulder 30 upon the needle-thread are described in my said Patent No. 1,115,663, and need not therefore be specifically described herein. 105

Having thus set forth the nature of the invention, what I claim herein is:—

1. In a sewing machine, in combination, a reciprocating needle, a circularly moving loop-taker provided with a loop-seizing 110 beak, loop-taker actuating means, and a loop-support adjacent the needle-path and adapted to hold out of the range of action of the point of the beak a needle-thread loop cast off by the beak. 115

2. In a sewing machine, in combination, a reciprocating needle, a circularly moving loop-taker provided with a loop-seizing beak, loop-taker actuating means, a loop-support adjacent the needle-path and adapted to hold out of the range of action of the point of the beak a needle-thread loop cast off by the beak, and a shield for the beak point adjacent said loop-support. 120

3. In a sewing machine, in combination, a reciprocating needle, a rotary loop-taker provided with a loop-seizing beak, a thread-case journaled therein over which the needle-thread loops are passed by the loop-taker beak and provided with loop-detaining 125 130

- means operative through a portion only of a rotation of the loop-taker, loop-taker actuating means, a loop-support adjacent the needle-path and adapted to hold out of the 5 range of action of the point of the beak a needle-thread loop cast off by the beak, and a shield positioned to overlie the beak point at the termination of the operative period of said detaining means.
- 10 4. In a sewing machine, in combination, a reciprocating needle, a circularly moving loop-taker provided with a loop-seizing beak, means connected with said loop-taker for imparting to the beak a plurality of excursions from loop-seizing position for each reciprocation of the needle, and a loop-support adjacent the needle-path and acting upon a needle-thread loop cast off by the beak in one excursion of the latter to hold it 15 out of the range of action of the point of the beak in the succeeding excursion thereof.
5. In a sewing machine, in combination, a reciprocating needle, a circularly moving loop-taker provided with a loop-seizing beak, actuating means therefor, and a loop-support sustained adjacent the needle-path independently of the loop-taker and adapted to hold out of the range of action of the point of the beak a needle-thread loop cast 20 off by the beak.
6. In a sewing machine, in combination, a reciprocating needle, a circularly moving loop-taker provided with a loop-seizing beak, actuating means therefor, and a loop-support movable differentially of the loop-taker and adapted to hold out of the range of action of the point of the beak a needle-thread loop cast off by the beak.
7. In a sewing machine, in combination, a 25 reciprocating needle, a circularly moving loop-taker provided with a loop-seizing beak, a thread-case journaled therein, means for restraining the thread-case against turning with the loop-taker, a reciprocating opening member for interrupting engagement of the thread-case with its holding means, and a loop-support sustained by said opening member and adapted to hold out of the range of action of the point of the beak 30 a needle-thread loop cast off by the beak.
8. In a sewing machine, in combination, a reciprocating needle, a circularly moving loop-taker provided with a loop-seizing beak, a thread-case journaled therein, means for restraining the thread-case against turning with the loop-taker, a reciprocating opening member for interrupting engagement of the thread-case with its holding means, a loop-support sustained by said 35 opening member and adapted to hold out of the range of action of the point of the beak a needle-thread loop cast off by the beak, an actuating element rigidly connected to and partaking of the circular movements of said loop-taker, and an operative connection be- 40
- tween said actuating element and the opening member.
9. In a sewing machine, in combination, a reciprocating needle, a circularly moving loop-taker provided with a loop-seizing beak, a thread-case journaled therein, means for restraining the thread-case against turning with the loop-taker, a lower thread pull-off element movable independently of the loop-taker, and a loop-support sustained in 45 fixed relation with said pull-off element and adapted to hold out of the range of action of the point of the beak a needle-thread loop previously cast off by the beak.
10. In a sewing machine, in combination, a reciprocating needle, a circularly moving loop-taker provided with a loop-seizing beak, a thread-case journaled therein, means for restraining the thread-case against turning with the loop-taker, a reciprocating opening member for interrupting engagement of the thread-case with its holding means, a lower-thread pull-off element sustained by and movable with said member, and a loop-support sustained by said opening member and adapted to hold out of the range of action of the point of the beak a needle-thread loop cast off by the beak.
11. In a sewing machine, in combination, a reciprocating needle, a loop-taker provided with a loop-seizing beak, actuating means for imparting to the loop-taker a plurality of excursions from loop-seizing position for each reciprocation of the needle, and a plurality of fingers sustained adjacent the needle-path, the one being adapted to shield the point of the loop-taker beak and the other to sustain a needle-thread loop cast off by the loop-taker beak and to hold it out of the range of action of the latter in a succeeding excursion.
12. In a sewing machine, in combination, a reciprocating needle, a loop-taker provided with a loop-seizing beak, actuating means for imparting to the loop-taker a plurality of excursions from loop-seizing position for each reciprocation of the needle, and a reciprocating member sustained at one side of the path of movement of the loop-taker beak and adjacent the needle-path and formed in the side adjacent the loop-taker with an undercut recess producing oppositely extending fingers of which the one is adapted to shield the point of the loop-taker beak and the other to sustain a needle-thread loop cast off by the loop-taker beak and to hold it out of the range of action of the latter in a succeeding excursion.
13. In a sewing machine, in combination, a reciprocating needle, a circularly moving loop-taker provided with a loop-seizing beak, a thread-case journaled therein, actuating means for imparting to the loop-taker a plurality of excursions from loop-seizing

position for each reciprocation of the needle, means for restraining the thread-case against turning with the loop-taker, and a reciprocating member sustained at one side of the path of movement of the loop-taker beak and provided with a shoulder engaging the thread-case to interrupt its contact with the holding means and formed in the side adjacent the loop-taker with an undercut recess producing oppositely extending fingers of which one is adapted to shield the point of the loop-taker beak and the other to sustain a needle-thread loop cast off by the loop-taker beak and to hold it out of the range of action of the latter in a succeeding excursion.

14. In a sewing machine, in combination, a reciprocating needle, a circularly moving loop-taker provided with a loop-seizing beak, a thread-case journaled therein, actuating means for imparting to the loop-taker a plurality of excursions from loop-seizing position for each reciprocation of the needle, means for restraining the thread-case against turning with the loop-taker, a reciprocating member sustained at one side of the path of movement of the loop-taker beak and provided with a shoulder engaging the thread-case to interrupt its contact with the holding means and formed in the side adjacent the loop-taker with an undercut recess producing oppositely extending

fingers of which one is adapted to shield the point of the loop-taker beak and the other to sustain a needle-thread loop cast off by the loop-taker beak and to hold it out of the range of action of the latter in a succeeding excursion, an actuating element rigidly connected to and partaking of the circular movements of said loop-taker, and an operative connection between said actuating element and the reciprocating member.

15. In a sewing machine, in combination, a reciprocating needle, a rotary loop-taker mounted for movement in a plane transverse to the needle-path and formed with a cup-shaped body having a peripheral flange-portion merging into a loop-seizing beak, and a second peripheral flange-portion merging into a fork disposed mainly in rear of the beak-point, said fork comprising a guard-finger disposed below the plane of movement of said beak-point and an upper discharge finger adapted to receive and detain a needle-thread loop drawn off the point of said beak.

In testimony whereof, I have signed my name to this specification, in the presence of two subscribing witnesses.

CHARLES F. GRAY.
